DESIGN FOR A BOTTLE HOOD

Samuel H. Berch, Los Angeles, Calif., assignor to
Western Dairy Products, Inc., Los Angeles,
Calif., a corporation of Maryland

Application May 23, 1936, Serial No. 62,791

Term of patent 14 years

To all whom it may concern:

Be it known that I, Samuel H. Berch, a citizen of the United States, residing at Los Angeles, in the county of Los Angeles and State of California, have invented a new, original, and ornamental Design for a Bottle Hood, of which the following is a specification, reference being had to the accompanying drawing, forming a part thereof.

The figure is a perspective view of a bottle hood showing my new design. As there shown, the hood is provided with a plurality of distinctive, downwardly extending tabular members.

I claim:

The ornamental design for a bottle hood, substantially as shown and described.

SAMUEL H. BERCH.
